UNITED STATES PATENT OFFICE.

AMOS O. HESS, OF SALEM, OHIO.

GATE.

SPECIFICATION forming part of Letters Patent No. 416,729, dated December 10, 1889.

Application filed September 4, 1889. Serial No. 322,969. (No model.)

To all whom it may concern:

Be it known that I, AMOS O. HESS, a citizen of the United States, residing at Salem, in the county of Montgomery and State of Ohio, have 5 invented certain new and useful Improvements in Gates; and I do hereby declare that the following is a full, clear, and exact description of the invention, which will enable others skilled in the art to which it appertains to 10 make and use the same, reference being had to the accompanying drawings, and to the letters of reference marked thereon, which form a part of this specification.

My invention relates to improvements in 15 gates of that form known as "farm-gates," the several features of which will be fully herein-after described, and set forth in the claim.

The object of my invention is to provide 20 against the sagging of the post to which the gate is hung by so constructing said gate that the outer end may be raised when sagging makes it necessary. I attain the object by the mechanism illustrated in the accompanying drawings, in which—

25 Figure I is a side elevation of the gate. Fig. II is a horizontal section of a part on line *x*, Fig. I.

Like letters designate like parts in the two figures.

30 A is a base-piece used to support the posts. B is the post to which the gate is hung, and into this are driven angular irons forming the pivots embraced by the straps D and E. The former hinge-strap is illustrated at D, Fig. 2. 35 The strap is bent, as shown, so that the two boards forming the upright are embraced thereby, and the bolt *o* completes the connection of the hinge to the gate.

The gate-uprights H and I are each composed of two boards, between which are held the boards F by the bolts *o* and *n*, which pass through the same and on which the horizontal boards can move.

40 The forward part of the gate is held up and nearly in a horizontal position by the diagonal brace G. The lower end of this brace is curved

and bears against a curved notch in the boards, forming the upright H. The bolt *u* is used to hold the end in position, and the bolt *7* enters one of a series of notches in the under edge 50 of the top board, and when the thumb-screw 1 is tightened the parts are made rigid.

To add greater rigidity to the gate, two boards J, forming vertical braces, are attached by bolt *6* to the bottom board, and these engage the under side of the diagonal braces and are fastened by the thumb-screw 2. The catch comprises the bar 4, with a pin to arrest its outward movement, and is held on the next to the bottom board between the bars 3 and 55 the upright I. It is carried out to enter a slot of post C by the flat spring 5, attached to the vertical brace. This catch serves to hold the gate shut.

The outer end of the gate may be raised or 60 lowered by shifting-bolt 7 in the notches of the top board, and the parts are more rigidly bound by the vertical brace, which is secured against the said diagonal brace, thus forming a gate sufficiently rigid, and yet adjustable, to 65 compensate for sagging of the post to which it is hung.

Having fully described my invention, what I claim, and desire to secure by Letters Patent, is—

70 In a gate, the combination, with its pivotally-connected uprights and horizontal members, of the diagonal brace engaging notches in the under edge of the top board, and the double vertical brace secured to the bottom board and 75 provided with a tightening-bolt, whereby it may be adjusted to support the diagonal brace in any of its positions, all substantially as shown.

In testimony that I claim the foregoing as 80 my own I affix my signature in presence of two witnesses.

AMOS O. HESS.
